BY

H.J. Sanders
ATTORNEY.

UNITED STATES PATENT OFFICE.

WILLIAM DAHLSTRAND, OF BELVIDERE, ILLINOIS.

FOUNTAIN BRUSH.

Application filed August 25, 1921. Serial No. 495,392.

To all whom it may concern:

Be it known that I, WILLIAM DAHLSTRAND, a citizen of the United States, residing at Belvidere, in the county of Boone and State 5 of Illinois, have invented certain new and useful Improvements in Fountain Brushes, of which the following is a specification.

This invention relates to improvements in fountain brushes and more particularly to 10 brushes of this type adapted primarily for use in washing automobiles. One object is to provide a brush of this type having a rotary head upon which two streams of water converge from a turbine motor, the 15 force of the two streams of water being neutralized as they come together upon the brush to avoid scratching or defacing the paint of the automobile. It is known that a stream of water directed forcibly upon an 20 automobile body will loosen particles of mud and other foreign matter by sheer force and drive such particles over the painted surface of the vehicle thus often scratching the same. This is effectively obviated by the use 25 of my invention. A further object is to provide a simple practical device of the kind that is compact, cheap to manufacture and efficient in operation.

With the foregoing and other objects in 30 view the invention consists in the combination and arrangement of parts to be herein-after fully described, pointed out in the appended claim and illustrated in the accompanying drawing which forms a part of this 35 application and in which—

Fig. 1 is a longitudinal sectional view through my improved fountain brush.

Fig. 2 is a section through the turbine motor and housing on line 2—2 of Fig. 1.

40 Like reference characters denote corresponding parts in both views.

The reference numeral 1 denotes a turbine housing, circular in cross section and provided with the handle 2. The casing is pro-

45 vided with the water intake pipe 3 adapted at its free end to make connection with a

water hose. The housing 1 is provided, further, with the nozzles 4, 5 that register with perforations in the housing at points more than 90 degrees apart about its periphery, 50 said nozzles converging toward each other to throw meeting streams of water upon the bristles 6 of the twisted wire shaft 7 that is secured to the tubular sleeve 8 that is made fast to and that rotates with the shaft 9 55 that rotates in a bearing 10 formed terminally of the brace bars 11 which bars are secured to the face plate 12 of the turbine housing, said housing being perforated for passage therethrough of the shaft 9 one end 60 of which is seated in a depression formed in the housing 1.

The turbine motor 1 is keyed to the shaft 9 and receives the stream of water which comes through the intake pipe 3 and is driven 65 thereby. From the turbine motor the water passes out through the nozzles 4, 5. In use the rotating bristles or brush head clean the vehicle of mud and other extraneous matter after the same has been softened by the 70 water.

What is claimed is—

In a fountain brush, a circular turbine casing, a rotary shaft journaled through said casing, a turbine motor within said 75 casing fast upon said shaft, a brush operatively connected to said shaft to rotate therewith, an intake pipe for said turbine casing having its delivery end opening directly upon said motor, and nozzles registering 80 with said turbine casing, said nozzles being spaced apart about the casing periphery and converging toward each other and toward said brush whereby meeting streams of water are played upon said brush. 85

In testimony that I claim the foregoing as my own I have hereto affixed my signature in the presence of two subscribing witnesses.

WILLIAM DAHLSTRAND.
